UNITED STATES PATENT OFFICE.

EDMOND F. TOOMY AND WILLIAM J. LAVERY, OF JERSEY CITY, NEW JERSEY.

NAME-PLATE FOR MAIL-BOXES.

1,146,907.

Specification of Letters Patent.

Patented July 20, 1915.

Application filed April 16, 1914. Serial No. 832,396.

To all whom it may concern:

Be it known that we, EDMOND F. TOOMY and WILLIAM J. LAVERY, citizens of the United States, and residing at Jersey City, 5 in the county of Hudson and State of New Jersey, have invented certain new and useful Improvements in Name-Plates for Mail-Boxes, of which the following is a specification, such as will enable those skilled in 10 the art to which it appertains to make and use the same.

This invention relates to name plates for mail boxes, and the object thereof is to provide an improved device of this class which 15 may be used on the door of a dwelling or other building, or in the entrance way, vestibule, or halls of apartment houses or other buildings, and the invention is fully disclosed in the following specification of which 20 the accompanying drawing forms a part, in which the separate parts of our improvement are designated by suitable reference characters in each of the views, and in which;—

25 Figure 1 is a front view of our improved name plate;—Fig. 2 a cross section on the line 2—2 of Fig. 1;—Fig. 3 a section on the line 3—3 of Fig. 1, and on an enlarged scale, and Fig. 4 a detail view showing a part of the 30 name plate detached, or a blank from which said part is formed.

In carrying our invention into effect, we provide a plate *a* preferably of brass and provided, preferably in the top portion 35 thereof, with a large rectangular opening *a*² closed by a transparent panel *b*, preferably of glass. The walls of the opening *a*² in the plate *a* are beveled forwardly and inwardly, and the walls of the panel *b* are correspondingly beveled, and said panel is inserted 40 from the back of said plate, and is held therein by any means, or in any manner. The plate *a* is provided on the back thereof and on the opposite sides of the opening *a*², 45 and in a transverse line substantially bisecting said opening with studs *a*³ to which are secured, by means of screws *c*, a transverse plate *d* formed from a blank *d*² shown in Fig. 4. The top edge of the plate *d* is provided centrally thereof with a semi-circular recess *d*³ and at the bottom edge thereof with forwardly directed lugs *d*⁴ which bear on the panel *b* and which are formed from lugs *d*⁵ at the bottom edge of 50 the blank *d*². The central part of the plate *d*

is set inwardly or forwardly parallel with the panel *b* forming L-shaped angle portions *d*⁶ through which the screws *c* are passed, and said plate is also preferably provided on the front face thereof with longitudinal 60 grooves *d*⁷ forming corresponding longitudinal ribs on the back thereof, the object of this construction being to strengthen said plate, if the latter be stamped from sheet metal, but it will be understood that the 65 plate *d*, as shown in Figs. 1 to 3 inclusive, may be cast if desired, and the exact form thereof, as herein shown and described, is not an essential feature.

Between the plate *d* and the panel *b* is a 70 card space *e* open at the top and into which a name card *f* may be dropped, and the object of the recesses *d*⁸ in the top of said plate is to facilitate the removal of said card from said space when necessary, and the bottom edge of the plate *d* is provided preferably centrally thereof, with a downwardly extending member *d*⁹ on which is placed, in the construction shown, the words “4th floor 75 right.”

The name plate shown in the drawing is intended for use in an apartment house, and the words “4th floor right”, indicate that the party whose name is on the card *f*, occupies the apartment at the right of the hall 80 on the fourth floor, but it will be understood that the legend “4th floor right” on the name plate, as shown, may be changed to indicate any apartment in the building. It will also be understood that our invention 85 is not limited to buildings having different apartments on each floor, or to buildings having separate apartments of any kind or location, and the use of the part *d*⁹ of the plate *d* is not an essential feature of our invention, and said part may or may not be 90 employed, according to circumstances.

A name plate of the class specified, when used in the vestibule, entrance way, or hallway of an apartment or other building, is 100 usually hinged at the top and locked at the bottom so that it may be swung forwardly to afford access to the box, back of the plate, but these features form no part of our invention and are not shown and described, 105 and if desired, our improved name plate may be used on the door, or any part of a building and is not necessarily used in connection with a mail box.

The forwardly directed lugs *d*⁴ at the bot- 110

tom of the plate *d* are intended primarily to close the bottom of the card space *e* so that a card, when dropped thereinto will be held therein, but the bottom of said space may be closed if desired, or partially so in any way, and, with the construction shown, the said lugs *d*⁴ may also serve to hold the panel *b* in place, or aid in holding said panel in place, and other changes in and modifications of the construction herein described may be made, within the scope of the appended claims, without departing from the spirit of our invention, or sacrificing its advantages.

Having fully described our invention, what we claim as new and desire to secure by Letters Patent is;—

1. A name plate provided with an opening closed by a transparent panel inserted from the rear side thereof, said plate being provided back of said panel with a member secured to the plate, having a portion spaced from the glass to form a receptacle for a card, and portions extending forwardly from the lower edge of said member, to bear against the transparent panel

and hold the same in place and also support the lower edge of said card.

2. A name plate for mail boxes, said plate being provided with an opening closed by a transparent panel inserted from the back of said plate and back of which is a detachable transverse member which in connection with said panel forms a card space open at the top and closed at the bottom by said transverse member which also holds said panel in place, said transverse member being also provided with a downwardly directed extension on which is placed a legend indicating the part of the building occupied by the party whose name appears on the card inserted into said card space.

In testimony that we claim the foregoing as our invention we have signed our names in presence of the subscribing witnesses this 15th day of April 1914.

EDMOND F. TOOMY.
WILLIAM J. LAVERY.
